UNITED STATES PATENT OFFICE

ALBERT C. BOYLE, JR., OF LARAMIE, WYOMING.

GRINDING AND POLISHING MACHINE.

1,134,944.

Specification of Letters Patent.

Patented Apr. 6, 1915.

Application filed May 9, 1912. Serial No. 696,176.

To all whom it may concern:

Be it known that I, ALBERT C. BOYLE, Jr., a citizen of the United States, residing at Laramie, in the county of Albany and State of Wyoming, have invented certain new and useful Improvements in Grinding and Polishing Machines, of which the following is a specification.

My invention relates to grinding and polishing machines and more particularly to machines of the type designed to be employed in preparing micro-sections of rocks, minerals, metals, ores or other substances whose formation can be determined only by the use of a microscope.

Minerals, rocks and other substances which are transparent in thin section, are by the use of my machine ground so thin that light can pass through them whereby their structure may be examined by transmitted light, while metals, ores and other similar substances which are almost always opaque and can thus be examined only by reflected light, are by means of my machine polished to such a degree that the light falling upon their sections is reflected and thus reveals the formation thereof.

Heretofore the micro-sections have been prepared mostly by hand or otherwise by more or less cumbersome machines which in their operation, depend to a great extent on the skill of trained workmen, and it is the object of the present invention to provide a machine of the class described, which being self-contained, is of very simple and durable construction, and which is well adapted to grind and polish micro-sections mechanically and automatically without the attention of skilled operatives.

A further object of my invention is to provide means whereby the abrasive material and water or other liquid used in the grinding and polishing process, are automatically fed onto the grinding surface after they have been impelled by centrifugal force to the peripheral portion of the same, the said means being adjustable for the purpose of selecting the material according to its size and specific gravity whereby different kinds of abrasive and water may be separately or simultaneously fed onto the grinding surface while the machine is in operation.

Other objects of my invention reside in

the provision of a construction whereby the specimens are moved across the grinding surface for the purpose of preventing the formation of ridges and of presenting the specimens to the action of the abradant in many different positions, in the provision of means by which the specimens are automatically maintained in frictional contact with the grinding surface, and in providing carriers by means of which a plurality of specimens may be ground or polished at one time by contact with one and the same grinding element.

A reservoir of oil is provided to automatically feed a lubricant to the principal bearing of the machine while it is in operation.

I attain the above enumerated objects by the mechanism illustrated in the accompanying drawings in the various views of which like parts are similarly designated, and in which—

Figure 1 represents a plan view of my improved grinding and polishing machine, Fig. 2, a central vertical section taken along the line 2—2, Fig. 1, Fig. 3, a horizontal section taken along the line 3—3, Fig. 2, drawn to a reduced scale, Fig. 4, a horizontal section through one of the rotary cylindrical carriers which support the specimen while being ground, Fig. 5, a fragmentary vertical section through the said carrier taken along the line 5—5, Fig. 4, and showing in elevation, one of the self-adjustable holders to which the specimens are attached, Fig. 6, a section through the peripheral portion of the lap-wheel employed in my machine, showing the rim in which the abrasive powders and liquids are classified by centrifugal force before being returned onto the grinding surface, and Fig. 7, a sectional view of the lower portion of one of the specimen-holders and adjacent portion of the carrier in which it is supported, showing a modified method of securing specimens thereto.

Referring more specifically to the drawings, my machine comprises a hollow base 2, which by an inwardly projecting flange 3, is divided into two communicating compartments the lower one of which houses the electric motor which supplies the motive power for the rotary elements comprised in the construction, while the upper compartment forms a bowl whose circumferential

wall provides a protective inclosure for the rotary lap-wheel and the specimens which frictionally engage the same.

The electric motor which necessarily must be of compact construction, comprises an annular stator 4 which is securely fastened within the lower compartment of the base which, as is clearly shown in Fig. 3 of the drawings, is provided with large openings 5 for ventilation purposes.

A step bearing 6 axially disposed within the base for the support of the rotary element of the motor, forms part of a motor base 7 which consists of the vertically-bored bearing 6, surrounded by an oil reservoir 8, and connected with a concentric rim 9 by radial spokes 10. The rim 9 is securely fastened by means of lag-screws 12 to inwardly projecting lugs on the base, and the bore of the bearing 6 is lined with a steel bushing 13 provided at its upper end with a flange 14 which in its upper face has a race for a series of balls 15 upon which the rotary element of the motor is supported.

The winding 16 of the rotor which is loosely fitted within the annular stator, is secured around a hood 17 which covers and surrounds the oil-reservoir 8 and which by means of a steel shaft 18 is rotatably fitted in the bushing 13 of the bearing 6 and supported upon the balls 15 in the race formed in the flange thereof. The shaft 18 which is fitted in a central opening of the hood is held in place thereon by means of a ring 35 nut 19 which occupies a recess in the upper surface of the hood, and an integral collar 20 which being disposed in a recess in the inner surface of the same, has a concentric groove complementary to the race in the flange of the bushing.

The reservoir 8 is provided at its bottom with a normally plugged opening 21 through which its contents may be drawn off, it is of sufficient size to contain a considerable quantity of oil which by capillary attraction is constantly fed to the ball bearing while the rotor is in motion, and the hood 17 is formed with a conoidal deflective surface 22 which extending partially into the reservoir, prevents the oil from spilling over the outer wall thereof.

The shaft 18 has in its upper portion, an axial, tapering socket for the support of the correspondingly formed shank 23 of the lap-wheel 24 which consists of a circular disk surrounded by an upwardly curving, interiorly concave rim 25 and provided in adjacency to said rim with a concentric, shallow depression 26.

Erected upon the lap in axial alinement with the tapering shank thereof, is a shaft 27 which at its upper end is rotatably fitted in a central bearing 28 which forms part of a spider 29 the downwardly curving, divergent legs of which are supported upon the

flanged rim of the base 2. The spider 29 is furthermore provided with three elongated vertical bearings 30 which are equidistantly arranged in a circle concentric with the bearing 28 and in which are journaled the shafts 31 of the rotary specimen carriers 32. Each of these carriers consists of a cylindrical shell provided with a bottom to which the shaft 31 is connected and which in its circumferential surface has a plurality of equidistant, vertically extending recesses 33, the outer openings of which are normally closed by means of vertically movable slides 34 for the purpose of providing sheaths in which, in practice, the specimen holders 35 are vertically movably disposed.

The holders 35, each consist of a stem which extends through the respective recess 33 and whose protruding lower end is enlarged in diameter to provide a chuck 36 which at its bottom surface is recessed to receive the specimen to be polished.

In case the specimens which in the drawings have been designated by the numeral 37, consist of rock, mineral or other irregular bodies, the recesses in the chucks of the holders, which are preferably dove-tailed in section, are filled with wax, cement or other plastic material in which the specimens are embedded so as to project beyond the lower surfaces of the same. If the specimens consist of metal and are of more regular form, they may be secured in the recesses of the holders by mechanical means such as the set-screw 38 shown in Fig. 7 of the drawings.

The holders are provided at their upper protruding ends with heads 39, the upper surfaces of which are engaged by disks 40 which are slidably mounted on headed posts 41, the threaded lower portions of which are secured in correspondingly threaded openings in lugs which form part of the walls of the recesses 33 in which the respective holders are disposed.

Springs 42 coiled around the posts between the heads thereof and the respective disks, tend to constantly maintain the specimens at the lower ends of the holders in frictional contact with the grinding surface of the lap-wheel 24 and stop-nuts 43 screwed upon the threaded portions of the post below the heads of the respective holders, are provided to limit the extent of their downward movement.

The shafts 31 of the carriers 32 are provided at their upper ends with worm-wheels 44 which bear upon the upper end-surfaces of the respective bearings 30 and which mesh respectively, with worms formed at the ends of shafts 45 which are rotatably mounted in boxes 46 on the spider 29 and which at their opposite ends carry worm-wheels 47 which are in operative engage-

ment with a 'worm 48 mounted at the upper end of the shaft 27 connected with the lap-wheel 24.

When by energization of the electric motor in the lower compartment of the base, the lap-wheel is rotated, the specimen holders will, by means of the above described gearing, be simultaneously rotated about their vertical axes at a rate of speed considerably less than that of the wheel, and the specimens at the ends of the holders 35 being held in contact with the upper surface of the lap by means of the springs 42, will be ground or polished by the abrasive action of the material fed onto the said surface until the downward movement of the holders is arrested by the respective stop-nuts 43.

As a result of the movement of the specimens across the lap, they are presented to the grinding force in an infinite number of positions and every part of each specimen, irrespective of its structure will thus at one time or another be subjected to the grinding or polishing action of the abradants on the lap. The formation of ridges in either the specimens or the surface of the wheel is by the movement of the former, positively avoided and the production of new and abnormal structures as often takes place in very soft metals and alloys when held in one position during the grinding process, is done away with.

To automatically feed the abrasive material and water or other liquid with which the lap is initially supplied onto the portion of the surface engaged by the specimens while the machine is in operation, I have provided a conduit 49 composed of two tubular members 50 and 51 which are adjustably connected by means of a union 52 attached at the end of an adjusting screw 53 which is mounted in a threaded block 54 secured upon the flanged rim of the base 2. The lower one, 51, of the two members has its lower end bent opposite to the direction of rotation of the lap 24 within or in close proximity to the concavity of the rim 25, and the other member 50 extends from the union upwardly and toward the shaft 27 and thence downwardly to a point above the grinding surface in adjacency to the center of the same.

It is obvious that to effectively grind or polish the specimens without changing their texture or structure by becoming heated, not only an abrasive powder but also a liquid must be constantly supplied to the grinding surface of the lap with which they are in frictional engagement.

As the lap-wheel rotates at a comparatively light rate of speed, the materials supplied upon its surface at the initial point of the operation, are, by centrifugal force moved to the periphery of the wheel until their outward motion is arrested by the

curved rim in whose concavity the constituents of the material will arrange themselves in layers according to their specific gravity, as is illustrated in Fig. 6 of the drawings in which the numerals 55, 56, 57 70 respectively designate the coarsest abrasive, the finer abrasive and the water or other liquid.

During the rotary movement of the lap, the matter into which the end of the conduit-member 51 extends, is drawn into and through the conduit 49 to be delivered through the orifice of the member 50 onto the central portion of the grinding surface and the character of the abrasive thus continuously fed onto the said surface, is readily varied in accordance with the requirements of the specimens under treatment, by adjustment of the screw 53.

The amounts of abrasive and liquid supplied to the grinding surface through the conduit depends on the diameter thereof and while in the drawings but one conduit has been shown, it will be readily understood that, if so desired, two similar conduits may 90 be employed to simultaneously feed an abrasive and a clear liquid onto the surface of the lap-wheel.

The electric motor which supplies the motive force for the various operating parts of the machine, is preferably designed to be operated by either a direct or alternating current and it may be connected by any suitable means with a conveniently located source of electricity; the lap-wheel is usually 100 made of cast-iron, copper, steel, zinc, lead or alloy; for grinding very hard specimens of steel, a carborundum or emery wheel is used in connection with the lap, and for polishing, cloth, chamois skin, leather or felt is 105 secured upon the face of the wheel.

The abrasive fed onto the grinding surface is varied in accordance with the character of the specimens to be ground, fine 110 carborundum or emery powders being most commonly used. The bearing of the rotor is constantly supplied with oil from the reservoir 8 by capillary attraction and, if necessary, a strip 56 of cloth or other fabric 115 may be suspended from the bearing into the reservoir, as is shown in Fig. 2 of the drawings, to more readily convey the oil from the latter to the parts of the bearing.

With respect to the methods shown and described for securing the specimens at the end of the holders, it will be understood that in preparing thin sections, the specimen after one of its sides is made flat and true by grinding, is cemented to a relatively thick piece of sheet glass or other material, which latter is then secured in the holder for final grinding, or, in case the specimens are not adapted to be held in the holders by cement or by the said screw, it may be necessary to 130

cement it in a metallic or porcelain base, which is then clamped in the holder.

Having thus described my invention what I claim and desire to secure by Letters-Pat-
5 ent is:

1. In a grinding and polishing machine, a rotary lap-wheel, a rotary carrier having a recess remote from its axis of rotation, a holder movable in said recess and having a
10 chuck adapted to rigidly hold a specimen for engagement with the face of said wheel, a spring on said carrier, engaging said holder to maintain the said specimen in continuous engagement with the said face, by
15 movement of said holder, and adjustable means for limiting the extent of said movement.
2. In a grinding and polishing machine, a rotary lap-wheel, a rotary carrier having a recess remote from its axis of rotation, a holder movable in said recess and having a
20 chuck adapted to rigidly hold a specimen for engagement with the face of said wheel, and a spring on said carrier engaging said
25 holder to maintain the said specimen in continuous engagement with the said face by movement of said holder.
3. In a grinding and polishing machine, the combination with a grinding surface, of
30 a movable holder adapted to hold a specimen in engagement therewith, and micro- metrically adjustable means for determining the extent of the movement of said holder toward said surface.
- 35 4. In a grinding and polishing machine, the combination with a grinding surface, of a headed holder movable by gravity to hold a specimen in engagement therewith, a screw, and a nut on said screw to determine
40 the extent of the movement of said holder toward said surface by engagement with its head.
- 45 5. In a grinding and polishing machine, the combination with a grinding surface, of a movable, headed holder adapted to hold a specimen for engagement therewith, a spring for moving said holder toward said surface, a screw, and a nut on said screw to determine the extent of the movement of
50 said holder toward said surface by engagement with said head.
- 55 6. In a grinding and polishing machine, the combination with a rotary grinding surface, of a holder movable by gravity toward said surface and at right angles thereto and having means for holding a metallurgical or petrographical specimen for frictional engagement with the same, so that it can be ground and polished by the movement of the
60 surface, to a thinness suitable for microscopic examination.
7. In a grinding and polishing machine, the combination with a rotary grinding sur-

face, of a holder movable at right angles thereto and having means for holding a 65 metallurgical or petrographical specimen in frictional engagement with said surface, so that it can be ground and polished by the movement thereof, to a thinness suitable for 70 microscopic examination; and means for feeding said holder, automatically, toward said surface to a preselected limit.

8. In a grinding and polishing machine, the combination with a rotary grinding surface, of a plurality of holders movable at 75 right angles thereto and each having means for holding a metallurgical or petrographical specimen for frictional engagement with said surface so that it can be ground and polished by the movement thereof, to a thin- 80 ness suitable for microscopic examination, and means adapted to rotate the said holders collectively about a common axis.

9. In a grinding and polishing machine, the combination with a rotary grinding sur- 85 face, of a plurality of holders movable at right angles thereto and each having means for holding a metallurgical or petrographical specimen in frictional engagement with said surface so that it can be ground and 90 polished by the movement thereof, to a thinness suitable for microscopic examination, means for feeding each holder, individually, toward said surface to a preselected limit, and means adapted to rotate the said holders 95 collectively about a common axis.

10. In a grinding and polishing machine, the combination with a rotary grinding surface, of a holder movable at right angles thereto and having a rotary movement about 100 an axis remote from its own axis, and means for feeding said holder toward said surface to a preselected limit, the said holder being adapted to hold a metallurgical or petro- 105 graphical specimen in frictional engage-
ment with said surface so that it can be ground and polished by the movement there-
of to a thinness suitable for microscopic ex-
amination.

11. In a grinding and polishing machine, 110 the combination with a rotary grinding surface, of a holder movable at right angles thereto and having means for holding a metallurgical or petrographical specimen for frictional engagement with said surface 115 so that it can be ground and polished by the movement thereof, to a thinness suitable for microscopic examination, and means to yieldingly and automatically press said holder toward said surface.

In testimony whereof I have affixed my signature in presence of two witnesses.

ALBERT C. BOYLE, JR.
